Primary Examiner — Karen E. Eldridge Powers*Assistant Examiner* — Jasmine Mlinarcik(74) *Attorney, Agent, or Firm* — Kaplan Breyer Schwarz & Ottesen, LLP(57) **CLAIM**

The ornamental design for a work glove, as shown and described.

DESCRIPTION

FIG. 1 is a view of the dorsal surface of a left-hand glove of an embodiment of a design for a work glove.

FIG. 2 is a view of the palmar surface of the left hand glove of an embodiment of the design for a work glove.

FIG. 3 is a top view of the dorsal surface of a left-hand glove of an embodiment of the design for a work glove.

FIG. 4 is a view of the radial side of the left-hand glove of an embodiment of the design for a work glove; and,

FIG. 5 is a view of the ulnar side of the left-hand glove of an embodiment of the design for a work glove.

The uniformly segmented broken lines shown on the glove illustrate stitching that forms a part of the claimed design.
